UNITED STATES PATENT OFFICE.

MICHAEL A. HAMMES, OF RACINE, WISCONSIN.

FIBER SHEATHING.

Application filed February 4, 1922. Serial No. 534,097.

To all whom it may concern:

Be it known that I, MICHAEL A. HAMMES, a citizen of the United States, and resident of Racine, in the county of Racine and State 5 of Wisconsin, have invented certain new and useful Improvements in Fiber Sheathings; and I do hereby declare that the following is a full, clear, and exact description thereof.

10 My invention relates to a fiber sheathing which is adapted to be used either on the inside or outside of buildings.

The general object of the invention is to provide a sheathing of this kind, to which 15 may be applied a coating of plaster or other plastic material, and which is provided with dead air spaces, by which an effective heat insulation is secured.

It is also an object of the invention to provide 20 a sheathing which is strong and durable, not likely to become cracked, and also a sheathing which will be moisture proof as well as offering the greatest resistance to the passage of heat.

25 My invention will be described with reference to the accompanying drawing in which

Figure 1 is a plan view of a section of sheathing before the plaster is applied there- 30 to.

Figure 2 is a cross sectional view of a similar section, but provided with a coating of plaster, and

Figure 3 is a detail sectional view on the 35 line 3—3 of Figure 1.

Referring more particularly to the drawing, the sheathing comprises a sheet 5 of heavy flat paper, having a corrugated sheet 6 secured thereto in the usual manner. A series 40 of stiff reinforcing wires 7 are then laid across the sheet 6 substantially perpendicular to the direction of the corrugations, and a second series of wires 8 are laid diagonally, and at each point of intersection with wires 7, 45 a loop 10 is formed which passes thru the sheets of paper and around the wire 7, thus providing a substantial and rigid structure.

The corrugated side of the paper is adapted to be filled with plaster, cement, or other plastic material, and this material may be 50 applied to the strips before they are laid, thus forming an article which may take the place of plaster-board, or this coating may be applied after the strips are laid on the building. The paper, before being manufactured into sheathing, is impregnated with 55 tar or other moisture proof material, and preferably the corrugated strip is formed, as shown, with the larger corrugations 12 forming air spaces between the two strips, 60 and the smaller corrugations 13 being in dove-tail shape, so as to provide a substantial key to retain the coating of plaster 11.

It will be understood that the precise structure shown is merely illustrative, and that other fastening means may be substituted for the loops 10, if desired. Also the plaster and corrugations may be duplicated on the other side of the flat sheet 5, in order to provide additional heat and moisture insulation. 70

It will therefore be understood that the invention is not limited to the specific structure shown, but includes all modifications which fall within the scope of the appended 75 claim.

I claim:

As an article of manufacture, a sheathing comprising a sheet of paper composed of a layer of flat paper and a layer of corrugated paper secured together so as to provide air spaces therebetween, and impregnated with 80 waterproofing material, reinforcing wires adjacent the corrugated surface and extending transversely to the corrugations thereof 85 and other reinforcing wires extending obliquely and looped over said transversely extending wires and passing through both layers of paper.

In testimony that I claim the foregoing 90 I have hereunto set my hand at Racine, in the county of Racine and State of Wisconsin.

MICHAEL A. HAMMES.
